(57) **CLAIM**

The ornamental design for a baking dish, as shown and
described.

DESCRIPTION

FIG. 1 is a top perspective view of an embodiment of a
baking dish.

FIG. 2 is a front view thereof, the opposite rear view being
a mirror image thereof.

FIG. 3 is a side view thereof, the opposite side view being
a mirror image thereof.

FIG. 4 is a top view thereof; and,

FIG. 5 is a bottom view thereof.

The evenly-spaced broken lines in the drawings are included
for purpose of illustrating portions of the baking dish that
form no part of the claimed design. The dot-dash-dot broken
lines in the drawings are included for the purpose of defining
the boundary of the claim, it being understood that the
dot-dash-dot broken lines themselves form no part of the
claimed design.
